United States Patent Office.

ROBERT HALE, OF CHICAGO, ILLINOIS.

Letters Patent No. 73,802, dated January 28, 1868.

IMPROVED COUCH OR CRADLE.

The Schedule referred to in these Letters Patent and making part of the same.

TO ALL WHOM IT MAY CONCERN:

Be it known that I, ROBERT HALE, of Chicago, in the county of Cook, and State of Illinois, have invented a new and improved Couch or Cradle; and I do hereby declare that the following is a full, clear, and exact description thereof, which will enable others skilled in the art to make and use the same, reference being had to the accompanying drawings, forming part of this specification.

Figure 1 is a perspective view of my improved couch or cradle.

Figure 2 is a side view of the same, partly in section, through the line *xx*, fig. 3.

Figure 3 is a cross-section of the same, taken through the line *yy*, fig. 2.

Similar letters of reference indicate corresponding parts.

My invention has for its object to furnish an improved suspended couch or cradle designed especially for children, but equally applicable for other persons, which shall be cheap, durable, simple in construction, and portable, being capable of being packed in a very small space, and carried in a travelling-basket or satchel; and it consists of an improved suspended couch or cradle, constructed and arranged as hereinabove more fully described.

A is a frame, which may be made of metallic rods or plates, and which is made in two or more parts jointed or hinged to each other, so that they may be folded together in one direction, while they cannot pass in the other direction farther than to be in a straight line with each other. This may be done by stop-pins in the one part, moving in curved slots in the other part, as shown in fig. 2. To the frame A, at each of its corners, are attached straps or cords, B, by means of hooks or rings passing through holes formed in the said frame, as shown in figs. 1, 2, and 3. The upper ends of the cords or straps B are attached to a ring, C, to which ring is also attached an adjustable cord, D, by securing it thereto passing it through a loop attached to said ring. The cord D is made adjustable by means of the slide or buckle E to which one end of the said cord is attached, while the other end is passed two or more times through holes formed in the said slide, so that by loosening the cord in the slide, the said slide may be moved up or down, and the height at which the cradle is suspended be adjusted at pleasure. F is the bottom or cover of the cradle or couch, which should be made of cloth, or equivalent material, and which is secured to the frame A by hooks attached to the under side of said cover, and which hook upon the edge of the frame A, as shown in figs. 2 and 3. The cover F should be put on so loose as to bag or hang down within the frame A far enough to prevent the child or other person lying in it from falling out. The couch or cradle may be suspended from the ceiling of a room or the roof of a car, by means of an eye-bolt or hook screwed into the said ceiling or roof, and to which the cord or strap D is attached. By means of this couch or cradle, persons travelling with small children may save themselves and others from much annoyance, and their children from much uneasiness and worrying by taking one of these cradles with them, and suspending it when required from the roof of the car, where it may be adjusted to swing above the heads of the passengers, and thus be entirely out of the way. When used at home, and for larger children or grown persons, it may, when not in use, be drawn up against the ceiling, so as to be entirely out of the way, thus greatly economizing space. If desired, the straps or cords upon one side of the frame may be replaced by bars or rods, having hooks or eyes formed upon their upper ends, so that it may be suspended from and against the wall of a room or the side of a car. But I prefer the construction first described.

I claim as new, and desire to secure by Letters Patent—

An improved portable suspended couch or cradle formed by the combination of the jointed frame A, removable cover or bottom F, straps or cords B, and adjustable cord or strap D, and slide or buckle E with each other, substantially as herein shown and described, and for the purpose set forth.

The above specification of my invention signed by me, this 2d day of December, 1867.
